METHOD OF DISPOSING OF REFINERY
WASTESMarvin L. Chappell, Berkeley, Calif., assignor to
Standard Oil Company of California, San
Francisco, Calif., a corporation of Delaware

Application May 13, 1938, Serial No. 207,764

3 Claims. (Cl. 23—177)

This invention relates to an improved method for disposing of waste products resulting from refining petroleum oil or other organic products with sulphuric acid, in which various acid sludges, sulphur bearing tarry residues, various mercaptan bearing gases and malodorous vapors are encountered, which must be disposed of in such a manner that the surrounding atmosphere will not be polluted or contaminated with poisonous irritants or malodorous refinery aerosols.

The conventional method for the ultimate disposal of all acid sludges or odorous compounds occurring in the refinery is high temperature oxidation, in which the combustible products are burned to carbon dioxide, water vapor, sulphur dioxide and sulphuric acid mist, and are then discharged from high stacks into the atmosphere.

However, much trouble is experienced by these known methods after the combustion operation due to the formation of sulphur trioxide, which unites with some of the water present in the products of combustion, forming what is known as sulphuric acid mist, a heavy white irritant gas which rapidly settles to the ground and is detrimental to vegetation, animal and human habitation.

The formation of sulphuric acid mist usually takes place after the combustion operation, and is principally due to contact of the heated sulphur dioxide bearing gases, which may contain from approximately 5 to 17 per cent by volume excess oxygen, with the heated brick work forming the stack, at temperatures between 900 and 1650° F.

The formation of sulphuric acid mist will not take place to any appreciable extent below 900° F. At temperatures above 1650° F. sulphuric acid mist is decomposed into sulphur dioxide and oxygen.

This application is an improvement on the method of disposing of refinery wastes, as described in United States Patent No. 1,929,675, patented October 10, 1933, by Marvin L. Chappell et al., which embodies burning refinery sulphur-bearing waste products to convert such products by combustion into carbon dioxide, water vapor, sulphur dioxide, at temperatures above 1650° F. and then quickly cooling the combustion products with sprays of water to approximately 900° F. or lower as they enter the stack to prevent formation of sulphuric acid mist.

By this Chappell et al. method the combustion heat is absorbed to a high extent by the introduced sprays of water and therefore is not com-

mercially available for heating purposes, such as for oil distillations or the production of steam in steam boilers.

Now, I have discovered improvements thereon in which the heat generated by the combustion of refinery waste products without the formation of sulphuric acid mist may be commercially utilized to a high extent for the production of pressure steam in steam boilers, oil distillations or other known operations embodying heat transfer.

Briefly stated, my invention comprises burning refinery waste products employing excess quantities of air in any known type furnace used for such purpose, either alone or in conjunction with other hydrocarbons, mixing a gaseous combustible reducing agent with the heated products of combustion before the temperature of the combustion products is reduced below 1650° F., in quantities sufficient to combine with and reduce the free oxygen content of said combustion products to less than 5 per cent by volume, thereby substantially preventing sulphur trioxide or sulphuric acid mist formation during passage thereafter through heat transfer equipment and conduit into the atmosphere.

The reducing agent may be any volatile hydrocarbon, natural gas or mixtures of methane with hydrogen and other hydrocarbon gases, or water gas consisting of hydrogen and carbon monoxide, and/or producer gas comprising carbon monoxide and nitrogen, and the like.

An object of the invention is to dispose of refinery waste products by combustion with excess quantities of air at high temperature, utilizing a part of the heat for generating pressure steam or oil heating purposes, without the formation of appreciable amounts of sulphuric acid mist, and then discharging the products of combustion through high stacks into the atmosphere.

Another object of the invention is to utilize acid sludges and acid tars derived from refining hydrocarbons with sulphuric acid, by combustion with excess amounts of air at high temperatures for generating steam in boilers or for oil heating purposes, without formation of appreciable amounts of sulphuric acid mist, and then discharging the products of combustion through a conduit into the atmosphere at a sufficient height so that air dilution therewith before it reaches the ground will not be detrimental to vegetation, animal or human habitation.

Another object of the invention is to provide means for the complete destruction by burning of acid sludges, mercaptans and other refinery aerosols, and partial utilization of the heat there-

from for commercial heating purposes without the formation of sulphuric acid mist.

Various other objects and advantages of the present invention will be apparent from the description of the preferred method or example embodying the invention, which will now be more fully explained by reference to the accompanying diagrammatic drawing.

In the drawing pipe 1, controlled by valve 2, 10 connects burner 4 to a supply of refinery waste products, such as acid sludge or tar, malodorous gases, or refinery aerosols. Pipe 12, controlled by valve 3, connects burner 4 to a steam supply. Pipe 10, controlled by valve 11, connects burner 15 4 to a supply of hydrocarbon gas or oil. Burner 4 is provided with air inlet passages 5. 9 represents a conduit or stack connected to furnace 6, through which the combustion products pass and are discharged into the atmosphere at the 20 required elevation. Pipe 8, controlled by valve 13, is connected with a source of a hydrocarbon gas, water gas, or producer gas, terminating within the furnace and provided therein with spray nozzles 15 for introducing the required 25 amounts of said gases. 14 is a water or oil heater coil through which water or oil is continuously passed and heated for the production of steam for distillation purposes, said coil 14 being connected to steam boiler equipment and/or oil 30 evaporation and fractionation equipment not shown.

The preferred process as carried out in the apparatus just described is as follows:

Furnace 6 is first heated to a temperature in 35 excess of 1650° F., preferably between 2000 and 2500° F., by the introduction and combustion of a hydrocarbon oil or gas with air. The hydrocarbon oil or gas is introduced into furnace 6 through burner 4 from pipe 10 controlled by 40 valve 11. The air to maintain combustion passes through inlet passageway 5 surrounding burner 4 and controlled by shutters or other mechanical means.

When furnace 6 has been heated to a temperature in excess of 1650° F., the flow of hydrocarbon oil or gas into furnace 6 is reduced or discontinued by closing, or partially closing, valve 11 in pipe 10. Then refinery sulphur bearing waste products either alone or mixed with hydrocarbon oil are caused to pass from their source of production or from storage through pipe 1 and into burner 4, the flow being controlled by operation of valve 2. At the same time a regulated flow of steam from pipe 12, controlled 55 by valve 3, is introduced into burner 4, which sprays the waste products into furnace 6 in a finely divided condition, wherein they are commingled with air coming through air inlet passages 5, in an amount sufficient to completely 60 consume or burn the spray of waste products with the formation of carbon dioxide, water vapor, and sulphur dioxide gases.

The quantity of air introduced into furnace 6 through air inlet passages 5 is regulated so as 65 to maintain an excess volume of free oxygen in the combustion gases of not less than 5 per cent as they pass over the top of "bridge wall" 7. The quantity of excess air introduced into furnace 6 depends upon the hydrocarbon content of the 70 waste product being burned.

For refinery waste products containing a high percentage of sulphuric acid, the percentage of air introduced into furnace 6 may be such that the excess free oxygen content in the combustion 75 gases may be approximately 10 to 17 per cent by

volume, although preferably this percentage of free oxygen in the combustion gases is maintained between 5 and 10 per cent.

In general, the quantity of air and quantity of hydrocarbon oil or gas introduced into furnace 5 6 along with waste products is governed by the temperature of the products of combustion passing over bridge wall 7, such temperature preferably being maintained between 2000 and 2500° F.

The completely oxidized products of combustion 10 at a temperature of approximately 2000 to 2500° F., having a free oxygen content ranging from 5 to 17 per cent by volume, after passing over bridge wall 7, are mixed with a sufficient quantity of a gaseous reducing agent from pipe 8 15 regulated by valve 13, which combines with and reduces the free oxygen content of the combustion gases to less than 5 per cent by volume, preferably ranging between 1/2 and 1 per cent. In case the combustion gases passing over bridge wall 7 20 contain 10 per cent by volume free oxygen, approximately 5 volumes of natural gas, and/or about 10 volumes of water gas (CO and H₂), and/or about 25 to 30 volumes of producer gas would be introduced for each 100 volumes of combustion gases calculated at like temperatures, to reduce the free oxygen content of the combustion gases to less than 1 per cent by volume.

In case intimate mixing of the oxidized products of combustion with the introduced gaseous 30 reducing agent is not immediately effected, larger amounts than those given above may be necessary to reduce the free oxygen content to less than 5 per cent by volume, determined by visual view of the stack gases discharging into the 35 atmosphere, such introduction of gaseous reducing agent being increased until white fumes no longer appear in the discharged stack gases.

After reduction of the free oxygen content to 1 per cent or less the said hot combustion gases 40 at temperatures ranging from about 2000 to 2500° F. are passed in heat exchange relationship to water or oil flowing through heater coil 14 and then into stack 9 which discharges the 45 gases at temperatures ranging from about 800 to 950° F., into the atmosphere without appreciable amounts of sulphuric acid mist therein.

While the process herein described is well adapted for carrying out the objects of the present invention, various modifications may be made, 50 such for example as the use of standard boiler tube equipment in place of heater coil 14, and the invention includes all such modifications as come within the scope of the appended claims.

I claim:

1. Process of burning sulfur-bearing petroleum waste products with substantially no formation of sulfur trioxide in the final combustion products, which comprises burning said waste products in a combustion zone in the presence of an 60 excess volume of oxygen of from about 5% to about 17% to effect substantially complete combustion at a temperature at least as high as that as which sulfur trioxide decomposes to form sulfur dioxide and oxygen so that substantially 65 no sulfur trioxide is formed, substantially reducing the proportion of excess oxygen in the products of combustion with substantially no loss of heat therefrom by introducing into said products of combustion in a second zone a sufficient 70 quantity of gaseous reducing agent to reduce the excess volume of oxygen therein to below about 1%, subsequently cooling said products of combustion to within that temperature range at which the equilibrium with respect to sulfur di- 75

- oxide, oxygen, and sulfur trioxide favors the formation of sulfur trioxide with substantially no formation of sulfur trioxide in said products of combustion.
5. 2. Process of disposing of oil refinery sulfur-bearing petroleum waste products, resulting from the treatment of petroleum products with sulfuric acid, by combustion with substantially no formation of sulfur trioxide in the final combustion products and with the utilization of the heat content resulting from the combustion, which comprises burning said waste products in a combustion zone in the presence of an excess volume of oxygen of from about 5% to about 17% at a temperature between about 2000° to about 2500° F., passing the resulting products of combustion containing the excess oxygen to a second zone and therein reducing the volume of said free oxygen below about 1% with substantially no loss of heat from said combustion products, by introducing into the resulting combustion products in said second zone a sufficient quantity of gaseous reducing agent to combine with the free oxygen and thereby reduce the excess volume thereof, contacting said hot products of combustion in heat exchange with an object to be heated and thereby cooling said products of combustion to a temperature below about 1650° F. and within the temperature range of 900°-1650° F. within which sulfur dioxide tends to react with oxygen to form sulfur trioxide but with substantially no formation of sulfur trioxide in said products of combustion, and then dis-

charging the final products of combustion substantially free from sulfur trioxide into the atmosphere.

3. Process of burning acid sludge, resulting from the treatment of petroleum products with sulfuric acid, with substantially no formation of sulfur trioxide in the final combustion products and with the utilization of the heat content resulting from the combustion, which comprises burning said acid sludge in a combustion zone 10 in the presence of an excess volume of oxygen greater than about 5% at a temperature above about 1650° F., so that substantially no sulfur trioxide is formed, reducing the volume of excess free oxygen in the resulting combustion products 15 to below about 1% with substantially no loss of heat from said combustion products by introducing into the resulting combustion products a sufficient quantity of gaseous reducing agent which combines with the free oxygen and thereby 20 reduces the excess volume thereof, contacting said hot products in a second zone of combustion in heat exchange with an object to be heated, and thereby cooling said products of combustion to a temperature below about 1650° F. and with- 25 in the temperature range of 900°-1650° F. within which sulfur dioxide tends to react with oxygen to form sulfur trioxide but with substantially no formation of sulfur trioxide in said products of combustion, and then discharging the final 30 products of combustion substantially free from sulfur trioxide into the atmosphere.
